UNITED STATES PATENT OFFICE.

FRANK STEVENS AND FREDERICK SPICKER, OF ROUNDUP, MONTANA.

DRILLING-MACHINE.

1,197,680.

Specification of Letters Patent. Patented Sept. 12, 1916.

Application filed June 14, 1915. Serial No. 33,913.

To all whom it may concern:

Be it known that we, FRANK STEVENS and FREDERICK SPICKER, citizens of the United States of America, residing at Roundup, in the county of Musselshell and State of Montana, have invented certain new and useful Improvements in Drilling-Machines, of which the following is a specification.

The present invention relates to improvements in drilling machines especially adapted for use in boring Artesian and oil wells of standard type.

The primary object of this invention is to improve in certain details the construction and operation of the drilling machine which is the subject of our Patent No. 1,077,649 patented November 4, 1913, as will be fully set forth hereinafter.

In the accompanying drawings we have illustrated one complete example of the physical embodiment of our invention constructed according to the best mode we have so far devised for the practical application of the principles of the invention.

Figure 1 is a side elevation of a portable well drilling machine constructed according to our invention. Fig. 2 is a top plan view, enlarged of the machine. Fig. 3 is a longitudinal vertical sectional view further enlarged of the rope or cable mechanism illustrating in detail our improved construction. Fig. 4 is a transverse detail sectional view on line 4-4 of Fig. 3.

The machine is supported upon a portable vehicle or truck including the rectangular frame 1 mounted upon the traction wheels 2, 2, 2, 2, and it will be understood that the machine may be drawn by horse power, or if desired the machine may be driven by its own power for transportation.

The tower 3 which is supported on a pivot 4 of the bracket 5 fixed to the frame, may be folded back on its pivot when the machine is not in operation, and thus provide for a more facile transportation of the machine. When in operative position as shown in Fig. 1, the tower is braced by means of a pair of brace rods 4', 4', attached at their upper ends to the tower at 5' and at 50 their lower ends fixed to brackets 7 on the frame by a bolt 8. In this manner the tower is supported in operative position so that the rope or cable 9 will operate over the pulley or sheave 10 journaled in the top of the tower. The tool 11 at the end of the cable is given a vertical reciprocating

stroke as readily understood, and this operation of the tool is primarily accomplished through the motor 12 supported at the rear of the machine frame. The motor may be of any suitable or desired type and its driving wheel 13 revolves the fly wheel 14 through the medium of the belt 15. The fly wheel is supported on the main shaft or "beater" shaft 16 which is journaled in the bearings 17 on the frame 1.

Through the medium of the main shaft the counter shaft or drum shaft 18 is revolved and the two shafts are geared together by means of the clutch gear 19 and the larger gear wheel 20. The clutch gear is slideable on the main shaft and co-acts with the fly wheel when the clutch 21 is closed as in Fig. 2. A lever 22 is pivoted on the frame at 23 and provided with the usual fork 24 and sleeve 25 by means of which the clutch 21 is operated.

The drum shaft 18 carries the usual winding drum 26 for the cable or rope 9 and the cable is wound upon this drum when it is revolved from the motor through the just described connections, but when it is desired to hold the rope or cable on the drum, the clutch 21 is of course opened and the drum gearing and drum remain idle.

In addition to the power mechanism for winding or unwinding the rope or cable on the drum, the drum may be turned manually by an attendant at the front of the drilling machine. Thus if it is desired to revolve and wind the drum only slightly the shaft 18 may be revolved through the medium of the worm wheel 27 on the shaft 18 and the worm gear 28 of the screw bar 29. This bar is supported in brackets 30 and may be turned by means of the hand wheel 31 at the front of the machine.

The fly wheel 14 which is loose on the shaft 16 may be brought into operative relation with the shaft (when not coupled up with the drum gearing) by means of the clutch mechanism 32 actuated by the shift lever 33. In Fig. 2 it will be apparent that the main shaft or beater shaft is made up of two sections having in addition to the two outer bearings 17, a pair of inner bearings 34, 34, on the frame bars 18, and between these two frame bars the adjoining ends of the shaft sections are connected by a pair of rings 35, 35 that are rigidly joined by the crossbar 36 so that the ends of the shaft sections are joined by an inflexible

connection thus rendering the shaft 16 rigid throughout its length. The cross bar has journalled thereon a pulley or sheave 37 against which the cable 9 at all times contacts. Thus, when the beater shaft is revolved to the left in Fig. 3 but to the right in Fig. 2, the pulley rides down the cable 9 and therefore lifts the tool 11 as will be understood. As the beater shaft revolves the pulley 37 is at all times in contact with the cable and the cable is guided between the two rings 35 35. In this manner many accidents and displacements of the cable are prevented as the two rings confine the cable at all times to its proper working position, as the operation of the machine lifts and permits the tool to fall alternately.

In connection with the cable mechanism we employ a tension device for taking up the slack of the cable, and an adjusting device by means of which the depth of the stroke of the tool is gaged. The tension device includes a frame 38 pivoted at 39 on the frame bars 1* at the rear of the drum. At their upper ends the sides of the frame are joined by a rod or bar 40 upon which a pulley or sheave 41 is free to revolve and also free to move laterally, and over this pulley the rope or cable passes from the drum. The cable passes downwardly from the pulley 41 and around a wide roller 42 on the rod or shaft 43 which connects the sides of the frame 38 below the pivot bar 39. The lower end of each side piece of the frame 38 has attached thereto by pivotal connection a draw bar 44 movable and guided in a perforated bracket 45 at the underside of the frame and held in normal position by means of the spring 46. Thus any pull on the rope to the left in Fig. 3 will be against the tension of the spring, and after the pull ceases the tension of the spring will take up the slack of the rope by pulling the lower end of the frame 38 to the right in Fig. 3. The length of the stroke of the tool is adjusted and determined by the position of the pulley 47 under which the cable passes from the roller 42 to the sheave 37. This pulley 47 revolves on a short shaft 48, and the shaft 48 is slidable in two parallel slotted brackets 49 fixed to the underside of the frame bars 1*. A draw bar 50 provided

with a bifurcated or forked end 51 is connected at one end to the shaft and this bar is slidable in the bracket 52 fixed to the 55 frame. At regular intervals on the upper side of the draw bar notches 53 are provided and a turn latch 54 pivoted at 55 on the frame is adapted to engage any one of these notches and hold the draw bar in adjusted position. Thus when the latch 54 is lifted in Fig. 3 the draw bar 53 may be drawn to the left carrying with it the pulley 47 which is guided in its slotted brackets. When the pulley is drawn to the left 65 in Fig. 3 the length of the stroke of the tool is decreased and when carried to the right the length of the stroke is increased.

At the front of the machine we illustrate a drum 56 pivoted upon the frame and provided with a friction wheel 57 and a pair of gear wheels 58 and 59. All of these wheels and the drum are supported in the frame 60 and the frame is bodily movable on the pivot 61 so that the friction wheel may 70 be brought into contact with the inner periphery of the drive wheel 14 and be driven thereby. A rope or cord 62 is wound about the drum and passes over the pulley 63 on the tower 3. This rope may be attached to 80 the tool 11 when not in use, or may be used as a fishing rope for the tool when the latter is lost or become displaced.

What we claim is:—

In a boring machine the combination with 85 a drum, rope and tool, of a rotary impact member comprising a sectional shaft with spaced ends, a wheel rigidly connecting said ends of the sectional shaft consisting of a pair of spaced rings concentrically mounted 90 on the shaft ends, a rigid eccentric connection between said rings and a friction wheel on the connection for the rope, and a movable pulley and means for holding said pulley in adjusted position for adjusting 95 the rope with relation to the friction wheel.

In testimony whereof we affix our signatures in presence of two witnesses.

FRANK STEVENS.
FRED SPICKER.
